UNITED STATES PATENT OFFICE.

WILLIAM P. STALEY, OF SEDALIA, MISSOURI.

LUBRICANT-ATOMIZER.

1,128,381.

Specification of Letters Patent.

Patented Feb. 16, 1915.

Application filed February 6, 1914. Serial No. 817,070.

To all whom it may concern:

Be it known that I, WILLIAM P. STALEY, a citizen of the United States, residing at Sedalia, in the county of Pettis and State of Missouri, have invented a new and useful Lubricant-Atomizer, of which the following is a specification.

The present invention appertains to a valve oil or lubricant atomizer for use in connection with automatic lubricating appliances, applicable to steam lines or supply pipes for steam engines, and aims primarily to provide in combination with an ordinary or prevailing type of lubricator, a novel and improved device for atomizing the lubricant fed with the steam into the cylinder or cylinders, whereby the valves, piston and other wearing parts may be effectively lubricated with a minimum expenditure of lubricant.

It is also the object of the present invention to provide an atomizer device of the nature indicated, embodying a unique assemblage of parts to best carry out the results desired, whereby the device will be practical and efficient in its use, and will be of simple and inexpensive construction.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a side elevation of a common lubricating apparatus applied to a steam line or supply pipe, and embodying the present invention. Fig. 2 is a longitudinal section of the atomizer, parts being shown in full. Figs. 3, 4 and 5, are cross sectional views taken on the lines 3-3, 4-4, and 5-5 of Fig. 2, respectively.

The lubricating apparatus, which is of a common or prevailing type, embodies the lubricator 2, containing the lubricant, such as valve oil or the like, and connected by means of a pipe 3, to the steam line or supply pipe 1, at the point 4. As illustrated, the steam line, or supply pipe 1 leads down-

wardly to the steam chest (not shown) so that it will be understood that the steam flows downwardly in the apparatus, as illustrated.

Ordinarily, the lubricator outlet is connected directly to the steam line or pipe 1, so that the lubricant is discharged directly into the steam line. This, however, has been found of disadvantage, inasmuch as the oil or lubricant will be carried into the steam chest, and thence through the valve or valves and into the cylinders, in drops, the oil or lubricant not being properly atomized, which would result in an excessive expenditure of lubricant, and in an inefficient lubrication of the valves and piston.

In carrying out the present invention, an oil and steam chamber or compartment 5 is disposed between the lubricator 2 and the steam pipe 1, the said chamber being preferably in the form of a vertical cylindrical casing, and having its upper and lower end portions, connected to the lubricator 2 and the steam pipe 1, respectively, by means of the pipe sections 6 and 7, in order that the lubricant passing from the lubricator 2 to the steam pipe, will be constrained to pass through the chamber 5. The upper end of the chamber 5 is also connected by means of a pipe section 9, to the steam pipe 1, at the point 10 intermediate the point 4 at which the pipe section 3 is attached, and the point 8 at which the pipe section 7 leading from the chamber 5 is attached.

From the foregoing general outline of the apparatus, it will be apparent that as the steam is admitted into the cylinder, the pressure at the point 8 will be lowered, and as a result of the higher pressure at the point 10, steam will be admitted through the pipe section 9 to the chamber 5 and the usual supply of lubricant will pass into the chamber 5 from the lubricator whereby the lubricant and steam are brought together in a peculiar manner, within the chamber 5, so as to atomize the lubricant which passes from the chamber 5 into the steam pipe and finally into the steam chest and cylinder.

The construction of the atomizer *per se* is as follows: The atomizer chamber or casing 5 is provided with a lateral nipple or coupling member 11 adjoining its upper end, through which the pipe section 6 leading from the lubricator 2 is attached, and is further provided with a lateral nipple or coupling member 12 adjoining its lower end,

to which the pipe section 7 leading to the steam pipe, is attached. The upper end of the casing or chamber 5 is open, and has a closure or cap 13 threaded or otherwise engaged therein, a nozzle tube 14 depending from the closure or plug 13 and coupling means 15 being provided on the plug, to which the pipe section 9 is attached. The nozzle tube 14 preferably has its lower end closed, and terminating adjoining the lower end or bottom of the casing 5, the nozzle tube also being disposed axially within the casing.

Mounted upon the nozzle tube 14 is a series of lubricant baffles, which are intended to catch or arrest the lubricant admitted from the lubricator 2, through the pipe section 6 engaged through the inlet nipple or port 11, whereby the steam discharged from the nozzle tube 14, will atomize the lubricant, as will hereinafter more fully appear. To this end, a series of concaved or dished baffle disks 16, 16' and 16'' are mounted upon the nozzle tube 14 at spaced points the uppermost baffle disk 16 being disposed immediately below the inner end of the pipe section 6, while the lowermost baffle disk 16'' is disposed adjoining the outlet 12. Immediately above the intermediate and lowermost baffle disk 16' and 16'' respectively, are disposed convexed or cambered baffle disk 17' and 17'', which are slightly smaller in diameter than and arranged in pairs with the respective disks 16' and 16''.

The lubricant arrested or caught by the several baffle disks, is caused to travel along the disks in a peculiar manner to subject the same to the action of steam discharged from the nozzle 14, as will hereinafter appear, and to this end, each of the disks 16, 16' and 16'' is provided with an annular series of openings or notches 18 surrounding the nozzle tube 14, and with the upstanding flanges or lips 19 at and coextensive with the outer edges of the openings 18. The baffle disks 17' and 17'' are each provided with a series of upstanding peripheral flanges or lips 20, which have the passage 21 between their ends.

Each pair of disks 16'—17' and 16''—17'', are connected by an annular series of upright or vertical stays or bars 22, which have their lower ends attached to the respective concaved disks, and which have their upper ends attached to the periphery of the respective convexed disks, adjoining or directly below the passages 21.

The nozzle tube 14 is provided with a plurality of radial outlet apertures 23 between the disks 16' and 17', and the disks 16'' and 17''. The apertures 23 permit the steam to be discharged from the nozzle tube 14 to pass outwardly from between the respective baffle disks.

The operation of the apparatus, including

the atomizer as above described in detail, is as follows. As intimated hereinbefore, when the pressure of the steam is lowered at the point 8, due to the admission of the steam into the cylinder, the steam at the point 10 will be at a higher pressure, than at the point 8, and a supply of steam will be admitted into the nozzle tube 14 from the pipe section 9. It will be evident that the lubricant passing through the inlet 11 from the lubricator, and the steam entering the casing 5 through the nozzle 14, will be brought together to carry out the functions desired, by the atomization of the lubricant in order that the lubricant may be carried off in the form of a vapor with the steam in leaving the atomizer to enter the steam chest with the greater portion of the steam passing directly along the steam line or pipe 1.

The drops of lubricant carried into the casing or chamber 5 from the lubricator 2, will be arrested or caught by the baffle disks 16, 16' and 16'', particularly the first mentioned one, which is arranged directly below the pipe section 6. The lubricant or oil will flow toward the center of the disk 16, or toward the nozzle tube 14, due to the concavity of the disk 16, and as a result the lubricant will flow around the flanges or lips 19 and through the openings 18, down the nozzle tube 14 to the convexed or cambered baffle disk 17'. The convexed disk 17' will shed the lubricant to the flanges or lips 20 and through the passages 21, from whence the lubricant will flow or run down the stays or spacing bars 22 to the peripheral portions of the succeeding baffle disk 16'. From the disk 16', the lubricant will flow through the respective openings 18, down the nozzle tube, to the next succeeding baffle disk 17', the lubricant passing around the disks, 17'' and 16'' in precisely the same manner as with the disks 17' and 16'.

It will be noted that the supply of steam admitted into the nozzle tube 14 will be discharged through the apertures 23 between the respective disks 16'—17' and 16''—17'', in order to so attach the lubricant flowing around the disks, as to atomize or vaporize the same, the current of steam uniting or amalgamating with the lubricant vapor, so that the mixture will pass through the pipe section 7 into the steam line or pipe 1 to commingle with the column of steam passing therethrough to the cylinder.

With the improved atomizer applied to the lubricating apparatus, the lubricant will not only be atomized and vaporized, but will be heated, to the same temperature as the steam, so that the lubricant will be conveyed in an atomized form into the steam chest, through the valve or valves and into the cylinder, whereby the valve or valves piston cylinder walls, and other wearing parts will be lubricated, to reduce friction to

a minimum, and with a minimum expenditure of lubricant or valve oil.

It will thus be obvious that the improved apparatus, as herein described, will be thoroughly efficient for the purposes indicated; whereby those disadvantages incident to the use of an ordinary lubricator, will be eliminated.

Having thus described the invention what is claimed as new is:—

1. A vaporizer of the character described, comprising a casing having a lubricant inlet at one end and having an outlet at its other end, a series of lubricant baffles between the inlet and outlet, and steam admitting means extending longitudinally of the chamber and having discharge means coacting with the baffles.

2. In a lubricating apparatus, a vaporizing chamber attachable to a steam line and having inner baffles, means for supplying lubricant to the chamber, and steam admitting means extending axially within the chamber, and having discharge means in coöperative relation with the baffles.

3. A vaporizer of the character described, comprising a chamber having a lubricant inlet at one end and an outlet at the other end, a longitudinal steam nozzle extending within the chamber and having lateral outlet apertures, and lubricant baffles disposed within the chamber in coöperative relation with the said nozzle.

4. A vaporizer of the character described, comprising a chamber having a lubricant inlet at one end, and an outlet at its other end, a steam nozzle disposed axially within the chamber and having lateral outlet apertures, and lubricant baffles surrounding the said nozzle.

5. In a vaporizer of the character described, a casing having an inlet and outlet at its respective ends, a nozzle tube disposed axially within the casing and having lateral

discharge apertures, and lubricant baffles 45 mounted upon the nozzle tube.

6. A vaporizer of the character described, comprising a casing having an inlet and outlet at its respective ends, a nozzle tube extending longitudinally within the casing 50 and having lateral outlet apertures, and alternately concaved and convexed baffle disks mounted upon the nozzle tube.

7. A vaporizer of the character described, comprising a casing having an inlet and 55 outlet at its respective ends, a nozzle tube extending longitudinally within the casing, and alternately convexed and concaved baffle disks mounted upon the nozzle tube, the concaved disks having openings adjoining 60 the nozzle tube, and the nozzle tube having outlet apertures between the convexed and concaved disks of each pair.

8. A vaporizer of the character described, comprising a casing having an inlet and outlet at its respective ends, a nozzle tube extending longitudinally within the casing, alternately convexed and concaved baffle disks mounted upon the nozzle tube, the concaved disks having openings adjoining 70 the nozzle tube and upstanding lips along the outer edges of the said openings, the convexed disks having upstanding peripheral flanges forming passages therebetween, the convexed and concaved disks of each 75 pair having members extending therebetween and leading from the said passages, and the nozzle tube having outlet apertures between the convexed and concaved disks of each pair.

In testimony that I claim the foregoing as my own, I have hereto affixed my signature in the presence of two witnesses.

WILLIAM P. STALEY.
